Primary Examiner — Mary Ann Calabrese*Assistant Examiner* — Mark David Wolfley(74) *Attorney, Agent, or Firm* — Boardman & Clark LLP**CLAIM**

The ornamental design for a chair, as shown and described.

DESCRIPTION

FIG. 1 is a top perspective view of the ornamental design of a chair.

FIG. 2 is a front elevation view of the design of FIG. 1.

FIG. 3 is a rear elevation view of the design of FIG. 1.

FIG. 4 is a left side elevation view of the design of FIG. 1.

FIG. 5 is a right side elevation view of the design of FIG. 1.

FIG. 6 is a top view of the design of FIG. 1; and,

FIG. 7 is a bottom view of the design of FIG. 1.

The broken lines shown in the drawings show portions of the chair which form no part of the claimed design.

1 Claim, 7 Drawing Sheets(56)
